UNITED STATES PATENT OFFICE.

CALEB JOSHUA BLAKELY, OF JANESVILLE, WISCONSIN, ASSIGNOR OF
ONE-THIRD TO BENJAMIN F. BOYDEN, 2D, OF FOXBOROUGH, MAS-
SACHUSETTS.

BURNISHING-MACHINE.

SPECIFICATION forming part of Letters Patent No. 392,944, dated November 13, 1888.

Application filed March 14, 1888. Serial No. 267,148. (No model.)

To all whom it may concern:

Be it known that I, CALEB JOSHUA BLAKELY, of Janesville, in the county of Rock and State of Wisconsin, have invented certain new and 5 useful Improvements in Boot and Shoe Burnishing and Polishing Machines; and I do hereby declare the following to be a full, clear, and exact description of the invention, such as will enable others skilled in the art to which 10 it appertains to make and use the same.

My invention relates to an improvement in boot and shoe burnishing and polishing machines.

The nature and object of my present invention consists in the provision of two sets of 15 burnishing apparatus mounted on one machine and driven by one shaft, so connected thereto that they will be independent in action with regard to each other, and be permitted to reciprocate and describe arcs of different lengths 20 to conduct different burnishing operations on opposite sides of the same machine.

A further object is to so construct a shoe and boot burnishing machine that it will be balanced in movement and prevented from jar 25 or objectionable vibration in its moving parts.

A further object is to provide a lamp-stand and lamps which may be used to heat the burnishing-tools while they are in position for 30 use.

A further object is to furnish the rotary shaft which drives the burnishing mechanism with brushes that may be employed to polish the burnished work and be in convenient position for such a purpose.

With these objects in view my invention consists in the construction of parts and their combination, in a manner that will be herein-after described, and indicated in the claims.

Referring to the drawings making a part of 40 this specification, Figure 1 is a front elevation of the machine in position for use. Fig. 2 is a rear elevation of the burnishing-machine complete. Fig. 3 is a plan view of the device.

Fig. 4 is a cross-section in elevation of the machine taken on the line xx , Fig. 3, to show the means of reciprocating the burnishers. Figs. 5 and 6 represent enlarged detail views of one of the rock-arms which carry the reciprocating 45 burnisher's supporting-arms. Figs. 7, 8,

9, and 10 are enlarged detail views of one rock-arm, eccentric, and pitman, which drive the burnisher-tool.

For convenience in use the operating mechanism of this burnishing and polishing machine is supported upon a vertical hollow column, A , of proper height, which is provided with a wide base, A^2 , to afford stability, the upwardly-tapering column being cut away on opposite sides at A^3 to lighten it, and also to 55 permit a belt, which engages a driving band-wheel, a , to have contact with another pulley on the main shaft of the machine, which will be fully described in its proper connection with other parts of the mechanism. 60

Within the column A , opposite the openings A^3 , the fast and loose pulleys a^2 are supported on a horizontal drive-shaft, A^4 , which also supports and rotates the band-wheel a when the fast pulley a^2 is speeded by a belt 65 (not shown) which transmits motion and power from a proper source. The upper end of the column A is extended laterally on each side to produce a base-plate, A' , on which the machinery is placed, which will now be described. 70 Two vertical bracket-stands, b b , are erected on the base-plate A' , which are of equal height and the same general form. These are provided with adjustable boxes o o on their upper ends to revolvably support the spindle B 75 horizontally. The spindle B , just mentioned, gives support to a pulley, a^2 , which is secured thereon near its center of length or in the same vertical plane with the band-wheel a , and thus permits the belt r to travel properly on the 80 faces of the wheel and pulley.

A balance-wheel, c , with a heavy rim is mounted upon the spindle B , near to the pulley a^2 . It, by momentum afforded, gives a smooth movement to reciprocating devices, 90 which will be explained, and prevents objectionable wearing motion or vibration of the whole machine when the burnishing-tools are in rapid motion.

Upon the base-plate A' , near its front edge, 95 there is an elongated cylindrical hub, B' , formed or secured to the plate. This hub is axially perforated for the reception of a round bar, I , which is made to fit the bore of the hub, and is secured in place within it by set-screws or 100

other means, so that ends of equal length will project beyond the true parallel ends of the cylindrical hub B'. (See Fig. 1.) The round bar I, from its position, forms with its projecting ends two horizontal fixed studs on which are mounted the similarly-formed rock-arms F, to have a rocking engagement of their elongated hubs F' thereon. The form of construction of these two arms is shown in Figs. 5 and 10 of the drawings.

It will be noticed that the rock-arms F are each slotted between the points y y, (see Fig. 6,) which slots afford means for the adjustable attachment thereto of the pitmen G, one of 15 which is shown in position in Fig. 1, and both as they are connected to the arms and the driving-eccentrics H in Fig. 3.

The eccentrics H are secured on the spindle B, near the outer ends of the same, so as to 20 cause the loosely-attached pitmen G to lie parallel to the sides of the rock-arms F, to which they are fastened by means which will be hereinafter explained. The method of connecting these parts is shown in the enlarged 25 detail views given in Figs. 9 and 10.

In Fig. 10, which is a top plan view of one of the rock-arms G and an attached pitman and eccentric, the end of the pitman G, which is connected to the rock-arm F by an adjustable stud, m, is broken into sections, thus exposing the thimble g', which is made separate but firmly inserted in the perforated end i of the pitman to provide a good wearing-surface, the thimble being made of hard brass, bronze, 30 hardened steel, or any other suitable metal that may be preferred. The other end of the stud m is secured to the rock-arm F by the insertion of its reduced and flattened body through the slot, to engage with the shoulder m', and be secured in this slot by a clamping-nut, or a set-bolt, m², as may be preferred.

It should be understood that the throw of each eccentric is preferably made the same, although this is not imperative, as, if it is desired, they 45 may be varied in this respect without detriment to the operation of the machine.

The two rock-arms F and pitmen G are alike in construction, generally speaking, the only changes made being such as are necessary 50 to adapt them to be located on the right and left sides of the machine. Upon the upper ends of the rock-arms F rounded bosses F³ are formed, which have squared projections p made on them to receive thereon the mating 55 perforated ends of the curved burnisher carrying-arms C, which are held in place by bolts which are inserted through holes p' made in the squared projections p, above mentioned.

The burnisher-arms C, which are removably 60 secured to the bosses of the rock-arms, as has been described, are preferably curved outwardly on each side of the machine, with their free ends projecting horizontally a proper height above the floor of the room in which 65 the machine is located, so that they will present the burnishers which are affixed to these

ends in convenient position for use by workmen who operate on the machine.

The metallic polishing-tools d d are made adjustable to the outer ends of the arms C, 70 which carry them, and are affixed securely by bolt-connection or other approved means, so that different forms of tools to finish the edges, shank, top, and heel of a shoe or boot may be attached quickly and exchanged when another 75 shape is needed. It is evident that the two sets of burnishing apparatus, one on each side of the machine, are distinct from each other, their only connection being the common support afforded by the base-plate A', and also in 80 having one source of motion and power to drive them.

The "irons" d, so called, are actually made of steel hardened and highly polished, they 85 being shaped to suit the work they are to perform, and as it is necessary that they be heated before use gas may be conducted to these tools by flexible hose in an obvious manner, which when ignited to burn from a proper burner will by contact of its flame heat the irons d 90 when this is necessary.

In some cases it may be preferred to employ a lamp instead of gas to heat the tools d d. With this end in view I provide lamps, one 95 for each side of the machine, which will direct by their extended wick-tubes a suitable flame upon the irons when needed. These lamps are supported upon bracket-plates K, that are provided with perforated bosses t, which are placed over and upon the outer extremities of 100 the extended ends of the rock-arm-supporting studs I.

The bracket-plates K may be made as shown on the right-hand side of the machine in Fig. 1, or with a deep retaining-flange, K², around 105 its edge, as shown on the left side in the same figure.

The perforated bosses t on the bracket-plates K answer two purposes. The first has already been indicated. The other consists in their use 110 as a retaining-abutment for the rock-arms F, the hubs F' of which are in contact with the adjacent ends of these bosses t. The other ends of the elongated hubs F' of rock-arms F are secured to rock easily, but without objectionable end-play, by the adjusting-nuts e e, 115 that have threaded engagement with the studs I, as shown in Fig. 1.

Upon one or both projecting ends of the spindle B, as well as the peripheral surface of the spindle at one or both its ends, brushes D are affixed, as shown, so that these brushes will be available for use by a workman who is 120 burnishing work on the irons d, these brushes, from their construction, being convenient to polish any portion of the burnished work, or the entire shoe, if necessary.

In the drawings, Fig. 3, I have shown a single brush attached to one end of shaft B; but it is evident that a similar brush can be attached to the opposite exposed end of said 125 shaft.

It will be understood from the foregoing description that the changing of adjustment of the ends of the pitmen G will cause the rock-arms F to have a greater sweep if these pitmen ends are secured in the elongated slots of the rock-arms near to the hubs F' of the same, and a change of adjustment of the pitmen toward the upper ends of the slots f will shorten the arc of vibration given to the burnishing-tools d, so that any desired reciprocatory motion may be transmitted to the burnishing-irons d d in the manner stated. It will also be apparent that the movement of one burnishing-iron may be adjusted so that it will travel through a longer arc than the other and with increased speed per inch of surface travel, although both eccentrics are of equal throw and actuated by the same spindle. This feature of my machine is of great advantage, as two workmen may be employed at one machine, and as one operator finishes the edge or heel with a short stroke the other party may operate with a long quick stroke on the shank of a boot or shoe, and they may exchange pieces, so that the work is expedited with less handling than usual in such operations.

It should be stated that the burnishing of top pieces at the toe and edge setting may be effectually performed on this machine by a proper form of irons.

In operating the machine from the position and height given to the burnishing-irons the workman will be enabled to hold the work against his breast to steady it and also apply heavy pressure with more ease than in other devices for the purpose.

If the eccentrics that drive the pitmen and attached rock-arms are set diametrically opposite each other with regard to throw of the same, the operation of these rock-arms will be alternate, and in consequence the machine will be prevented from weaving or having an objectionable side vibration that might result if both moved simultaneously or together. If, however, the base is on a good foundation, this provision will not be necessary and the machine will work smoothly and perform rapidly and efficiently.

Many slight changes might be made in the details of construction of this device without a departure from the spirit or scope of my invention; hence I do not wish to confine myself to the exact forms herein shown; but,

Having fully described my invention, what I claim as new, and desire to secure by Letters Patent, is—

1. In the herein-described machine, the combination, with a rotary spindle, of a balance-wheel, two eccentrics and flexible brushes affixed to the spindle, two rock-arms carrying burnishers, and pitmen mounted on the eccentrics and adjustably secured to the rock-arms, substantially as set forth. 60

2. In the herein-described machine, the combination, with two vibrating arms, and burnishers adjustably attached to the vibrating arms, of a spindle, eccentrics thereon, and pitmen actuated by the eccentrics and adjustably secured to the vibrating arms, whereby longer or shorter strokes, as desired, may be imparted to the burnishers, substantially as set forth. 65

3. In the herein-described machine, the combination, with a spindle having an eccentric thereon, a longitudinally-slotted rock-arm, and a burnishing-tool adjustably secured to the free end of said rock-arm, of a pitman mounted at one end on the eccentric and adjustably connected at its other end to the rock-arm, substantially as set forth. 75

4. In the herein-described machine, the combination, with a vertical column, a bed-plate fixed to the top of the column, a drive-shaft, fast and loose pulleys, a band-wheel secured on the drive-shaft, and a spindle revolvably mounted on the bed-plate, of two eccentrics, two pitmen, and two rock-arms which are slotted to adapt them to be adjustably connected to the pitmen and receive different motion from the same spindle, substantially as set forth. 80

5. In the herein-described machine, the combination, with a column having an enlarged base and open on opposite sides, a bed-plate affixed to the top of the column, a drive-shaft supported to revolve within the column, two pulleys, and a band-wheel secured on the drive-shaft, of a horizontal spindle revolvably sustained in brackets on the bed-plate, a pulley, a balance-wheel, and two eccentrics mounted on the spindle to revolve with it, two pitmen, two burnisher-arms, burnishing-tools secured to these arms, and two slotted rock-arms which are supported to move independently and are adjustably attached to the pitmen to be rocked by them, substantially as set forth. 90

In testimony whereof I have signed this specification in the presence of two subscribing witnesses.

CALEB JOSHUA BLAKELY.
